UNITED STATES PATENT OFFICE.

MAX POLITZER, OF NEW YORK, N. Y., ASSIGNOR TO EUGENE J. FRAENKELL, OF NEW YORK, N. Y.

DOLL.

1,171,977.

Specification of Letters Patent.

Patented Feb. 15, 1916.

Application filed April 7, 1909, Serial No. 488,501. Renewed July 1, 1914. Serial No. 848,482.

To all whom it may concern:

Be it known that I, MAX POLITZER, a subject of the King of Hungary, residing at New York city, county of New York, and State of New York, have invented certain new and useful Improvements in Dolls, fully described and represented in the following specification and the accompanying drawings, forming a part of the same.

10 The object of the invention is to provide an improved doll which may be adjusted or positioned to represent either an animal, or a doll having a human face and dressed all in fur, or, as it might be, a doll with the 15 body of an animal and a child's or other human face.

To these ends the invention consists in an animal doll, such as the well known Teddy bear doll, having the back of its head formed 20 to represent a human face and having its head preferably pivoted to turn on its body so that with the head turned to one position the doll viewed from the front will appear as a Teddy bear or other toy animal, and 25 with its head turned half around will appear as an ordinary doll having a human face and dressed all in fur, or as a doll with a human face and the body of an animal.

The accompanying drawings show a 30 Teddy bear doll constructed to embody the invention in a preferred form.

In said drawings, Figure 1 is a front quartering view of the doll, showing its animal face turned toward the front. Fig. 2 is 35 a front view of the head and upper part of the body, showing the head turned half way around from the position shown in Fig. 1 to show the child's face. Fig. 3 is a section of the head and upper part of the 40 body taken on a plane extending through from front to rear, and with the head in the position shown in Fig. 1.

Referring to the drawings, the body 10 of the doll including its arms and legs may be 45 formed in any usual or suitable manner, and will preferably be covered with suitable material, such as plush, to represent fur. The head 11 is formed to represent the head of a bear except that on the side opposite to 50 the bear face 12, the head is formed to represent a child's face as shown at 13. The head may be made in any suitable manner, but is preferably formed of a filling of hair or other suitable material covered with

plush or other material to represent fur, except for the portion which forms the child's face. The child's face may be formed in any suitable manner, but is preferably formed by using an ordinary molded face such as is commonly used on dolls, and 60 setting the same into an opening cut in the plush or other material with which the greater portion of the head is covered, the edges of the plush being sewed or otherwise secured about the child's face so as to give 65 the appearance of a hood, as seen in Fig. 2.

The head is secured to the body by means permitting it to be turned on the body, so that either the bear face or the child's face may be turned to face toward the front. 70 The means shown in Fig. 3 for so pivotally securing the head to the body comprises two disks of heavy card-board or other suitable material 14, one inside the lower part of the head and the other inside the upper part 75 of the body, and a pivot pin 15 extending through the two disks and through the body and head covering between the disks. Dished washers 16 are inserted between the ends of the pivot pin and the disks 14, and 80 the ends of the pin are formed to hold the disks and washers together. The head covering may be secured to the upper disk 14 by cords or threads 17 extending into the filling of the head or in any other suitable 85 manner, as by pasting, and the body covering may also be pasted or otherwise secured to the lower disk 14.

What is claimed is:

1. An animal doll having its body and its head except for a portion on one side thereof formed to represent the body and head of an animal and covered with material to represent fur, and having its head formed to represent a human face on the side which 95 is not covered with the material representing fur and on the opposite side to represent the face of an animal, the covering material extending about the human face to have the appearance of a hood, and the head 100 including the covering material thereon being vertically pivoted to the body to permit either face to be turned to the front.

2. A toy comprising in combination a body, and a head for said body, said head 105 having two faces thereon looking in opposite directions, one of said faces resembling that of a bear and the covering of said

head being arranged to form projections serving as ears for said bear's face, the other of said faces resembling that of a person and the cover of said head being arranged around said person's face in the form of a cowl whereby said projections serve likewise to give a clownish effect.

In testimony whereof, I have hereunto set my hand, in the presence of two subscribing witnesses.

MAX POLITZER.
